UNITED STATES PATENT OFFICE.

ALFRED HENRY MCNEIL, OF HIGHAMS PARK, ENGLAND.

ELECTRIC FIRE-ALARM AND THERMO-INDICATOR.

No. 891,948.

Specification of Letters Patent.

Patented June 30, 1908.

Application filed November 11, 1907. Serial No. 401,707.

To all whom it may concern:

Be it known that I, ALFRED HENRY MCNEIL, a subject of the King of Great Britain and Ireland, residing at No. 43 Beech Hall road, Highams Park, in the county of Essex, England, have invented certain new and useful Improvements in Electric Fire-Alarms and Thermo-Indicators; and I do hereby declare the following to be a full, clear, and exact description of the invention, such as will enable others skilled in the art to which it appertains to make and use the same.

This invention relates to electric fire alarms and thermo-indicators of the kind wherein electric contacts are closed by the action of metal strips which are fixed at both ends and deflected towards the contacts or towards operating devices connected therewith to complete an electric circuit when an abnormal rise of temperature occurs. Hitherto in apparatus of this type it has been the practice to employ a single metal strip adapted to press a movable contact against a fixed contact screw adjustable by means of a pointer moving over a suitably graduated dial.

Now according to this invention two metal strips are employed, and two movable contacts each operatively connected with one of the strips, but both arranged to move in the same path and in the same direction. One of the thermal strips is made more sensitive to changes of temperature than the other strip, and its contact is so arranged behind that actuated by the less sensitive strip, that under normal changes of temperature the two contacts move in the same direction without coming together, but on a sudden rise in the temperature being produced, the contact operated by the more sensitive strip will move at a quicker rate than the contact in front of it and bear against the slower moving contact thus completing the alarm circuit. In order to insure that the alarm shall also act even on a gradual rise of temperature should such temperature exceed a predetermined limit, a stop is provided to arrest the leading contact when such limit is reached to allow the other contact to overtake it and complete the circuit. The stop may also form an electrical contact and close the circuit when the leading movable contact bears against it.

In one way of carrying the invention into practice the two thermal strips are arranged side by side and fixed at their ends to pro-

jections on a base box. One of the strips is made less sensitive than the other by forming it of thicker metal and each strip has a plunger attached to it at or near the middle of its length, which passes through a hole, gland or flexible diaphragm into the box. The contacts are supported on an insulating base fixed in the box and comprise flat springs arranged in the paths of the plungers which have insulated ends. One of the springs carries an adjusting screw and a dial and moves in front of the other contact which is on the end of the other spring. The spring carrying the leading contact is operated by the plunger of the less sensitive thermal strip, and an adjustable fixed stop is provided to limit the motion of this contact as predetermined.

In the accompanying drawings Figure 1 is a front view of a thermally operated contact apparatus constructed according to this invention, Fig. 2 is a longitudinal section, and Fig. 3 is a back view with the cover removed, Fig. 4 is an enlarged transverse section and Fig. 5 is a plan showing the junction box for the leads with its cover removed.

The two thermal strips *a a'* are arranged side by side and fixed at their ends to projections *b* on a box or casing *c* in which the electrical contacts are inclosed. Both strips are deflected towards the casing *c* and have separate plungers *d d'* attached to them which pass through stuffing boxes *e e'* into the casing *c*.

As shown in section in Fig. 4 the thermal strip *a* is made thicker than the strip *a'* in order to render it less sensitive than the strip *a'* to changes of temperature, thus for a given change of temperature the plunger *d* connected with the thermal strip *a* will move at a slower rate than the plunger *d'* of the strip *a'*.

The thermal strips are protected by an openwork shield plate *f* fixed by screws to projections *c'* on the casing *c*.

In the interior of the casing *c* is fixed a plate or slab *g* of insulating material provided with openings *g'* for the passage of the plungers *d d'* and supporting movable contacts *h h'* carried on spring arms *i i'* which are held against the inner ends of the respective operating plungers *d d'*. Any movement of the thermal strips is thus communicated through their plungers *d d'* to the spring arms *i i'* and contacts *h h'* which are arranged a short distance apart and in line with an adjustable screw stop *j* carried by a bracket *j'*

on the plate g . The stop j may be either insulated or may form an electrical contact as shown to close the alarm circuit when impinged upon by the contact h .

5 An adjusting screw i^2 is provided on the contact arm i and bears on the end of the plunger d . Both adjusting screws j i^2 are provided with adjustable dials k k' and pointers so arranged that the contacts can be caused to close the circuit at any temperature indicated on the dials.

10 For the connection of the electrical leads m a box or chamber c^2 is cast on or fixed to the casing c and provided with a detachable cover plate c^3 held in position by screws. The leads are held by the screws n n' screwed into brass plates o o' in a block of insulating material p in the chamber c^2 . Short flexible conductors not shown fixed by screws o^3 o^4 15 to the plates o o' electrically connect the said plates with the contact screws i i' and bracket j' through the blocks o^5 o^6 .

20 The lid c^4 of the casing c is tightly fixed by screws a layer of packing being interposed, and the box is fixed in position on a wall, ceiling or other support by a bracket r cast on the casing.

25 In operation the plungers d d' which are tipped with insulating material actuate the corresponding contacts h h' the contact h operated by the less sensitive strip a moving in front of the contact h' and thus preventing the alarm circuit being closed by ordinary temperature fluctuations due to atmospheric 30 changes, artificial heating of buildings and the like. Should however the rise of temperature although gradual exceed a predetermined amount the leading contact h is arrested by the stop j to enable the contact h' 35 to overtake it and close the circuit. Or if the stop j forms a contact the circuit is closed as soon as the moving contact h reaches it. A sudden abnormal rise of temperature due to an outbreak of fire in the vicinity of the apparatus causes the contact h' to move quickly 40 against the contact h to close the alarm circuit.

45 It will be seen that by employing movable contacts as described the apparatus can be

set to operate at lower temperatures than 50 hitherto.

What I claim and desire to secure by Letters Patent is:—

1. An electric fire alarm apparatus comprising two thermal strips, one of which is 55 more sensitive to changes in temperature than the other, and movable contacts operatively connected with said strips respectively and arranged to move in the same path in the same direction, and an adjustably fixed stop arranged in the path of the moving contacts. 60

2. An electric fire alarm apparatus comprising a pair of thermal strips fixed at their ends and formed of different sensitiveness to 65 changes of temperature, plungers connected to the strips, electrical contact arms in the paths of the plungers and supporting contacts arranged to move one behind the other in approximately the same path, an adjustable fixed stop or contact in the path of the moving contacts, and a casing inclosing the contacts substantially as described. 70

3. A fire alarm apparatus comprising thermal strips of different sensitiveness to 75 temperature changes, plungers connected with said strips and electrical contacts connected to move one in advance of the other in the paths of the plungers and of each other. 80

4. In a fire alarm apparatus, the combination of a casing, two thermal strips arranged side by side within said casing and one being less sensitive to changes in temperature than the other, plungers attached to said strips, spring members carrying contacts arranged 85 in the paths of said plungers and of each other, an adjusting screw carried by one of said members and having a dial and moving in front of the other contact, and means for limiting the movement of the leading contact. 90

In testimony whereof I have affixed my signature, in presence of two witnesses.

ALFRED HENRY McNEIL.

Witnesses:

ALFRED NUTTING,
PERCY PHILLIPPS.
